UNITED STATES PATENT OFFICE

MAURICE ANDERSON, OF EDGEWOOD, RHODE ISLAND, ASSIGNOR TO LEVY, ANDERSON CO., INC., A CORPORATION OF RHODE ISLAND

DESIGN FOR A JEWELLED BRACELET CHAIN

Application filed July 9, 1931. Serial No. 40,474. Term of patent 3½ years.

To all whom it may concern:

Be it known that I, MAURICE ANDERSON, a citizen of the United States of America, residing in Edgewood, county of Providence, State of Rhode Island, have invented a new, original, and ornamental Design for a Jewelled Bracelet Chain, of which the following is a specification, reference being had to the accompanying drawings, forming a part thereof.

Fig. 1 is a top plan view of a jewelled bracelet chain showing my new design; Fig. 2 is a side elevation; Fig. 3 is a section on line 3—3 of Fig. 1 with the gems not in section of the same; and Fig. 4 is a perspective view of one of the link units of the chain.

I claim:

The ornamental design for a jewelled bracelet chain, substantially as shown.

MAURICE ANDERSON.
